(57) **CLAIM**

The ornamental design for a drill driver tool, as shown and described.

DESCRIPTION

FIG. 1 is a front perspective view of a design of a drill driver tool;

FIG. 2 is a front elevation view of the drill driver tool of FIG. 1;

FIG. 3 is a rear elevation view of the drill driver tool of FIG. 1;

FIG. 4 is a right side elevation view of the drill driver tool of FIG. 1;

FIG. 5 is a left side elevation view of the drill driver tool of FIG. 1;

FIG. 6 is a top plan view of the drill driver tool of FIG. 1; and, FIG. 7 is a bottom plan view of the drill driver tool of FIG. 1. The broken lines shown in the drawings illustrate portions of the drill driver tool that form no part of the claimed design.

1 Claim, 7 Drawing Sheets
